UNITED STATES PATENT OFFICE.

WILLIAM H. ROOK, JR., OF AKRON, OHIO, ASSIGNOR TO GEORGE R. HILL, OF AKRON, OHIO.

STRUCTURAL BLOCK.

1,274,455.

Specification of Letters Patent.

Patented Aug. 6, 1918.

Application filed December 24, 1914. Serial No. 878,913.

To all whom it may concern:

Be it known that I, WILLIAM H. ROOK, Jr., a citizen of the United States, residing at Akron, in the county of Summit and State 5 of Ohio, have invented a certain new and useful Improvement in Structural Blocks, of which the following is a full, clear, and exact description.

This invention relates to blocks for structural purposes, especially for the construction of sewers and other tubular and curved structures, the blocks being manufactured from plastic clay or the like, by means of standard or other approved expressing 10 presses; and the object of the invention is to provide means for insuring the proper distribution of the mortar or other cementitious matter in the end joints of such blocks, so as to effect secure and watertight joints 15 at these points.

The invention consists of a block having its ends provided with transverse tapering recesses and a mortar-receiving strip, of any suitable material, on which the mortar is 20 placed while the blocks are being laid and are slightly separated and while the strip rests upon the edges of the bottoms of the recesses of adjacent blocks, so that when the blocks are forced into proper relation, the strip 25 will ride up the bottoms of the recesses on which it rests and will displace the mortar and properly distribute it within the recesses and between the adjacent edges of the blocks above the strip, to thereby seal 30 the joint. This strip may also serve as a reinforce against radial displacement of the blocks or the parting of the joint, and to 35 that extent obviates the necessity of lap-jointing the ends of the blocks, as I will 40 proceed now to explain and finally claim.

In the accompanying drawings illustrating the invention, in the several figures of which like parts are similarly designated, Figure 1 is a perspective view illustrating 45 two blocks and their interposed strip partly assembled. Fig. 2 is a side elevation showing the blocks separated and the strip in place and supplied with a quantity of mortar and ready to be joined. Fig. 3 is a side 50 elevation with the joint formed. Fig. 4 is a longitudinal section showing three blocks united, and illustrating two forms of the strip, either or both of which may be used. Fig. 5 is a transverse section of two

blocks placed side by side. Fig. 6 is a perspective view of the preferred form of strip. Fig. 7 is a perspective view of the modified form of strip shown at the right-hand side of Fig. 4.

I have shown my invention as applied to 60 a preferred form of hollow or cellular clay sewer block, of segmental form, with dovetail side joints, but it is to be understood that the invention is not limited to any particular kind or construction of block, so 65 long as its ends may be recessed to receive the strip in the manner and for the purpose herein explained.

The block shown has the arcuate outer wall 1 and the similar concentric inner wall 70 2, and the side walls 3 and 4 arranged radially and preferably provided with suitable interlocking means, such as the tongue 5 on one side and the complementary groove 6 on the opposite side, both tongue and groove 75 extending longitudinally and coterminously with the side walls, and adapted to interlock when like blocks are arranged side by side. The side walls are connected transversely by the substantially central web 7, 80 and this web and the outer and inner walls are connected by a substantially central perpendicular partition 8, the said web and partition dividing the block into cells for drainage and reinforcing purposes. 85

The ends of the block are provided with the transversely arranged recesses 9 extending longitudinally into the side walls and perpendicular partition, and located preferably below the transverse web and between it and the inner wall, or, in other words, to one side of the transverse median plane of the block. The tops and bottoms of these recesses are inclined and converge 90 toward the interior of the block. 95

When like blocks are arranged end for end, as in Fig. 2, and before they are intimately abutted against one another, a mortar receiving and distributing strip, of any form and material, is laid upon the bottoms of the recesses in adjacent blocks, and then mortar or other joint sealing material is piled up upon the strip and the blocks then forced toward each other to close the space between their ends. As the blocks approach one another, the strip rides up the bottoms of the recesses and into the recesses, 100 and the mortar is thus distributed in the re- 105

cesses and forced by the movement of the strip upwardly against the median plane or inner wall, and between the adjacent ends of the blocks above the strip so as to effect 5 the sealing of the joint. The preferred form of strip comprises a trough-like piece 10, having the inclined bottom 11 and side flanges 12; although a flat strip 13, such as shown at the right-hand side of Fig. 4 and 10 in Fig. 7, may be used; or both forms of strips may be used in the same structure.

In constructing a sewer of the hollow blocks, such as herein shown and described, the invert blocks are first alined end for end 15 and the strips are placed in the end recesses and the mortar applied, and when the blocks are forced together the mortar will be distributed in the recesses against the median plane, or inner wall, and between the joint 20 as above described, and some of the mortar will be forced into the hollows of the blocks upon opposite sides of the central partitions 8 and under the inner walls 2 of the blocks and thus form an additional mortar lock 25 between the blocks against radial displacement; and when constructing the arch, so also a quantity of mortar will be distributed into the hollows of the blocks upon opposite sides of the central partitions 8 and under 30 the central webs 7 and thus form an additional mortar lock against radial displacement of the arch blocks.

It will be understood that when the invert blocks are being laid, the strips are so placed as to force the mortar upwardly toward the center of the sewer, and when the arch blocks are being laid, the strips are so placed as to force the mortar upwardly toward the outside of the sewer. The outside 40 of the invert blocks will thus be left open at the joints and sealed on their inner or flow-line side and these open joints aid distribution of the seepage-water. The arch blocks, on the contrary, are left open at their 45 joints on the inside of the sewer and are sealed on the outside. The joints may be

pointed up from the inside of the sewer after it is completed, if desired.

I am aware that reinforcing bars, rods and plates have been used in the end joints 50 of structural blocks, but so far as I know none of these has served or has been capable of serving as a mortar-receiving and a mortar-distributing device in the manner herein explained. 55

What I claim is:—

1. A structural block, having an outer wall, an inner wall, and connecting side walls, the ends of the block provided with transverse recesses extending inwardly in 60 the direction of the length of the block and arranged below a median plane, the tops and bottoms of said recesses being inclined, and a mortar-receiving strip arranged in the recesses in the adjacent ends of alined blocks 65 and adapted to be moved radially by coaction with the inclines of said recesses to distribute the mortar between the ends of the blocks as the blocks are moved toward one another. 70

2. A hollow segmental structural block, having an outer wall, an inner wall and opposite side walls, a transverse web connecting the side walls, and a perpendicular partition connecting the outer and inner walls 75 and the transverse web and located between the side walls, the ends of the block provided with recesses in the side walls and perpendicular partition and located adjacent to the transverse web, the tops and bottoms of said 80 recesses being inclined for the purpose specified, and a trough-like strip for use in the said recesses in the ends of adjacent blocks to receive and distribute the joint-sealing mortar. 85

In testimony whereof I have hereunto set my hand this fifteenth day of December, A. D. 1914.

WILLIAM H. ROOK, JR.
